CLAIM

The ornamental design for a display screen or portion thereof with icon, as shown and described.

DESCRIPTION

FIG. 1 is a front view of a display screen or portion thereof with icon, showing my new design; and,

FIG. 2 is a front view of a display screen or portion thereof with icon of FIG. 1, in which a mobile terminal in broken line is provided to illustrate an example environment.

The broken lines showing a display screen or portion thereof form no part of the claimed design.

1 Claim, 2 Drawing Sheets

FIG. 1

FIG. 2
